Specification of Letters Patent.

Patented Mar. 3, 1914.

Application filed September 28, 1910. Serial No. 584,201.

To all whom it may concern:

Be it known that I, SAMUEL A. NEIDICH, of Edgewater Park, in the State of New Jersey, have invented a certain new and useful Improvement in Duplicating-Machines, whereof the following is a specification, reference being had to the accompanying drawings.

My invention relates to machines adapted for printing and is particularly applicable to a machine constructed in accordance with my invention described in application Serial #584,201 filed September 28, 1910, for Letters Patent of the United States.

Such a machine in its preferred form includes a rotary printing couple comprising a type carrying drum and a platen, the latter being movable away from said drum to render the couple inoperative; paper feeding mechanism comprising two rollers one of which is movable away from the other to render them inoperative, and a cam which is rotatably adjustable with respect to the drum to render said feeding mechanism operative and inoperative in definite relation to the location of the printing form on the drum. Said platen is provided with a detent which normally detains it in operative relation with the drum, and a spring which tends to shift the platen into inoperative position when said detent is released. The form of my invention herein shown as applied to such a machine as above mentioned includes an electrically operative releasing mechanism for said detent, controlled by two electric switches, one carried by the feeding mechanism and both operated by said cam, so that, said releasing mechanism and switches being included in an electric circuit with a source of current, said releasing mechanism is operated and the printing couple rendered inoperative when both of said switches are closed, such closure being consequent upon the omission of a sheet of paper when it should be between said feed rollers.

My invention includes the various novel features of construction and arrangement hereinafter more definitely specified.

In the drawings: Figure I is an elevation of the left hand side of a duplicating machine mounted upon a suitable supporting stand in connection with a paper sheet feed chute and provided with an electric motor and stop mechanism embodying my inven-

tion. Fig. II is a fragmentary elevation of the right hand side of the duplicating machine shown in Fig. I. Fig. III is an outside elevation of the electric controlling mechanism shown at the right hand side of said stand in Fig. I. Fig. IV is an inside elevation of said controlling mechanism shown in Fig. III. Fig. V is a fragmentary vertical sectional view of said duplicating machine, taken on the line V, V in Figs. II and IV. Fig. VI is a vertical longitudinal sectional view of said machine, taken on the line VI—VI in Fig. VII. Fig. VII is a transverse sectional view of said machine, taken longitudinally with respect to said type carrying drum and platen. Fig. VIII is a sectional elevation of the electrically controlled releasing mechanism shown in dotted lines in Fig. V. Fig. IX is a diagram of the electrical connections indicated in the other figures.

In said figures, 1 is the frame of the duplicating machine comprising the rotary printing couple consisting of the drum 2 which is fixed on the rotary shaft 3, and the platen 4 which rotates loosely on the normally stationary shaft 5. Said drum 2 is conveniently provided with the stationary hooks 7 and the oscillatory hooks 8 to detachably engage the flexible chase 9 constructed to hold movable set type 10 as in the application aforesaid, but may be otherwise adapted to hold printing forms of different sizes. Said platen 4 has means to shift its axis toward and away from said drum 2, including the eccentrics 11 and 12 on its shaft 5 and the impression lever 14 to turn said shaft. Said platen is normally retained in co-operative relation with said drum 3, as shown in Figs. II and VI, by the detent including the plunger 15 which engages the socket 16 in the flange 17 of said lever 14. Said detent is carried by the releasing lever 18 which is fulcrumed in the stud 19 on the frame 1 and has at its opposite end the manually operative push button plunger 20, which is pressed outwardly by the spring 21. The spring 22 which encircles said platen shaft 5 and is attached thereto at one end, being held at the other end in said frame 1, tends to turn said shaft in the direction of the arrow shown in Fig. II, when released; so that when said detent 15 is withdrawn by inward movement of said releasing lever 18, said platen is turned

into its inoperative position, shown in Fig. II, wherein the flange 17 rests against the stop stud 23. Said detent 15 may be manually released by said button plunger 20, but I also provide automatically operative electrically controlled releasing mechanism for said detent, comprising the electro-magnet 24 shown in Figs. V and VIII having the oscillatory armature 25 pivoted at 26 in the box 27 and having the spring 28 tending to thrust it outward from the electro-magnet to the position shown in said figure. When in said position, said armature rests against the stop wire 29 and upholds the latch-lever 30 which is pivoted at 31 in said box 27 and has the recess 32 for the stop pin 34 on the tripping lever 35 so as to normally hold the latter in the position shown, against the stress of its spring 36 which encircles the pivot 37 of said lever 35 and tends to throw the latter and the releasing lever 18 inward when said armature is drawn toward the electro-magnet far enough to release said catch lever and permit the latter to fall and free the pin 34 of the tripping lever. It will be seen from Fig. VIII that this tripping lever 35 is a bell-crank having a substantially horizontal arm projecting outwardly from the hinge pin 37 and passing through an opening in the frame plate 1, so that its extreme portion is exposed and constitutes a finger piece to return this lever or hinged member 35 and the latch-lever 30 to normal position. This return of the latch levers 30 is caused by the pins 34 engaging the shoulder provided by the forward wall of the recess 32 in the latch lever. When the pin engages this shoulder it rocks the latch lever about its own pivot 31 and thereby raises its rear end to allow the armature to spring beneath it. As hereinafter described, said automatic releasing mechanism is arranged to be electrically operated in accordance with the position of the paper feeding mechanism, which as shown in Fig. VI includes the feed roller 38 journaled in said frame 1 above the table 39 but idly rotary with its axis stationary. Said feed roller 38 is opposed by and driven by the pressure of the feed roller 40 below said table 39 having rubber faces to engage the cut sheets of paper 42. Said roller 40 is raised to cooperative relation with said roller 38 by the rock shaft 43 having the lever arms 45, in which said shaft is journaled, and the spring 46 tending to turn said shaft in the direction of the arrows shown in Figs. VI and II; one end of said spring 46 being connected to said shaft 43 and the other end being held in frame 1 as indicated in dotted lines in Fig. II. Said arms 45 also carry the cross bar 47 having the paper stop fingers 48 in registry with openings in the guide plate 49 and table 39, so that when said arms 45 are

lowered each paper sheet 42 may be thrust against said fingers to insure its proper angular relation with the machine before being gripped by the upward movement of said roller 40 against the roller 38. Said stop fingers 48 being raised when the paper sheets 42 are thus gripped, they are fed into the machine by said rollers; said roller 40 being positively rotated by its gear 52 which is engaged by the gear 54 which turns loosely on said shaft 43 and is driven by the platen gear 55, which engages the gear 56 on the drum 2. Said shaft 43 is turned against the pressure of said spring 46 to lower said roller 40 and stop fingers 48 by the lever arm 58 on said shaft 43 having the stud shaft 59 extending through the slot 60 in the frame 1 and carrying exterior thereto the friction roller 63 in position to be encountered by the high portion 64 of the cam 65. Said cam is rotatably adjustable with respect to the drum 2 so that the paper feeding operation aforesaid may be initiated in predetermined relation to the position of the printing form 10 on said drum 2; said cam being held in adjusted position by the screw 66 shown in Fig. I. Said drum 2 and platen 4 and the parts connected therewith as above described may be manually rotated by means of the drum shaft handle 67 shown in Fig. I. However, as indicated in Fig. VI said platen gear 55 is engaged by the gear 68 on the shaft 69 which extends through the frame 1 as shown in Fig. I and is provided with the belt wheel 71 connected by the driving belt 72 with the belt wheel 73 on the counter shaft 74 of the electric motor 75. As indicated in Fig. I said motor 75 has the conductors 76 leading to the plug 77 in the socket 78 on the panel 79 supported by the stand 80 and having the conductors 81 leading to the service plug 82, so that as indicated in Fig. IX, said motor may be included in circuit with the rheostat 83 and the switch 84, and when the latter is closed as indicated in Fig. IX the speed of the motor and consequent speed of the machine may be adjustably determined by manipulation of the handle 85 on said rheostat 83. As shown in Figs. III and IV said switch 84 has the push buttons 87 and 88 to respectively close and open it and as indicated in Fig. IX it not only controls the circuit to said motor 75 but contemporaneously controls the stop mechanism circuit 89 including the battery 90 connected by the conductor 91 with the releasing magnet coils 24. The conductor 93 connects said coils 24 with the switch terminal 94 which as indicated in Figs. II and V is a flat spring mounted on the insulating block 95 in the frame 1 and having the screw 96 by which it may be adjustably set away from said block; said screw 96 having the jam nut 97 to secure it in adjusted position as shown in Fig. II. 130

Said switch member 94 is opposed by the resilient switch member 98 which is secured in rigid relation with the shaft 43 by the clamp screw 99 shown in Fig. V, so that said switch member 98 is oscillated with the paper feeding mechanism, above described; the arrangement being such that when the cam 65, turns the arm 58 into inoperative position, said switch is opened, and when said 5 cam permits said arm to return to the operative position of the feed roller 40, said switch is closed, unless a sheet of paper 42 is presented between said rollers 38 and 40, as indicated in Fig. IX. The arm 98 is made 10 comparatively long, as shown, so as to multiply the range of movement adjacent to the switch point 94 compared with the movement of the roller 40. Thus the presence or 15 absence of even a very thin sheet of paper 20 between the rollers 38 and 40 may determine whether the switch 98, 94 will be open or closed.

It being the purpose of the stop mechanism to operate said platen releasing mechanism and render the printing couple inoperative only when a sheet 42 is omitted at 25 the instant when it should be present between said rollers 40 and 38; it may be observed that if the stop mechanism circuit 30 were controlled only by said switch on the feeding mechanism the machine would be stopped each time said rollers 40 and 38 came together between successive sheets 42 being properly fed to the machine. Therefore, I include another switch in said circuit, comprising the plunger 100, pressed by the spring 101 in the insulating block 102 on the frame 1 so as to be closed by the high portion 64 of said cam 65 on the drum 2, as 35 indicated in Fig. IX, when the forward edge of each sheet 42 should be presented between the rollers 38 and 40 against the stop fingers 48.

Any convenient means may be employed 40 to furnish ink for the printing impressions, for instance, either said printing form 10, or an ink transfer sheet of textile fabric 104 which is detachably held thereover by the stationary studs 105 and flexible resilient 45 leashes 106 engaging the metal plates 108 and 109 at the respectively opposite ends of said sheet, may be reinked after each printing impression by the mechanism illustrated in Fig. VI. As shown, such mechanism includes the rubber faced ink transfer roller 110 which has the gear 112 engaging the gears 56 on the drum 2 and is normally presented in the position shown in Fig. VI to transfer ink to said sheet 104 or form 10. Said inking mechanism which is supported 50 by the carriage 113, adjustable toward and away from the drum 2, also includes the rollers 114, 115, 116 and 117 having means 55 cooperating to turn them and intermittently deposit a definite, adjustably variable amount

of ink 120 upon said transfer roller 110. The supply of said ink 120 is upheld by and between said rollers 116 and 117 and a pair of ink gates 121 which are pressed between said rollers by the spring arms 123 on the cross heads 124 which are adjustable toward and away from each other and are secured in adjusted position by the thumb nuts 125 on the bolts 126.

The mechanism above described may be 75 used as follows: The type 10 being set in the desired form in the flexible chase 9, said chase is attached to the drum 2 and covered with the ink transfer sheet 104 as shown in Fig. VI. The guides 127 on the paper chute 80 128 shown in Fig. I being set to direct cut sheets of paper 42 of the desired size in the desired relation to the width of said type form; the cam 65 is rotatably adjusted on said drum so that when each sheet 42 is presented against the stop fingers 48 it will be gripped at the proper instant to be drawn 85 between said drum and the platen in such relation as to locate the printed impression thereon in the desired position with respect to the length of said sheet.

The inking system described acts to coat the transfer roller with a film of ink sufficient to replace upon the transfer sheet 104 or type 10 at each impression the amount of 90 ink which is removed therefrom by each impression of the type form. A sheet of paper 42 being then inserted over the table 39 beneath the guide plate 49 against the stop fingers 48, and, said drum 2 being turned in the direction of the arrow marked thereon in Fig. VI, said feed roller 40 grips said sheet 42 against the feed roller 38 to draw it between said drum 2 and platen 4, print it, and discharge it over the rollers 130, on the shaft 131 which is rotated by its gear 132 engaging the gear 68 on the shaft 69. Said rollers have corrugated soft rubber faces which engage said sheets and direct them against the inclined guide strips 134 shown 100 in Fig. VI, so that said sheets fall into the rack 135 as shown in Fig. I.

Although the operation of the entire machine as above described may be initiated, regulated and terminated by manipulation 110 of the electric controlling mechanism for the motor shown in Fig. I; the operator may at any instant during such operation press the button 20 to operate the lever 18 and thus render the platen 4 inoperative and 115 terminate the printing operation without stopping the machine.

Although I find it convenient to provide the machine with the electric motor and controlling mechanism connected therewith as 120 indicated in Figs. I and IX, it is to be understood that said motor and its circuit may be entirely omitted and the machine operated by hand in conjunction with the electrically controlled releasing mechanism 125

above described. Therefore, I do not desire to limit myself to the precise details of construction and arrangement above described as it is obvious that various modifications 5 may be made therein without departing from the essential features of my invention as defined in the appended claims.

I claim:

1. The combination with a rotary printing couple; of mechanism arranged to feed sheets of paper between said couple including a feed roller mounted to rotate on a normally stationary axis and another feed roller mounted to rotate in opposition to 15 said first feed roller upon an axis movable toward and away from the latter; means arranged to render said couple inoperative when released; an electrically operative releasing mechanism; an electric switch comprising a normally stationary member and a member carried by and arranged to oscillate with said movable feed roller; a spring tending to shift said movable roller into contact with said other roller; and an electric circuit including said switch, said releasing mechanism and a source of current; whereby said releasing mechanism is operated and the printing couple rendered inoperative when said switch is closed, such 20 closure being consequent upon the omission of a sheet of paper when it should be present between said feed rollers.

2. The combination with a rotary printing couple; of mechanism arranged to feed sheets of paper between said couple including a feed roller mounted to rotate on a normally stationary axis and another feed roller mounted to rotate in opposition to 35 said first feed roller upon an axis movable toward and away from the latter; means arranged to render said couple inoperative when released; an electrically operative releasing mechanism; an electric switch in operative relation with said movable feed 40 roller; a spring tending to shift said movable roller into contact with said other roller; and an electric circuit including said switch, said releasing mechanism and a source of current; whereby said releasing mechanism is operated and the printing couple rendered inoperative when said switch is closed, such closure being consequent upon the omission of a sheet of paper 45 when it should be present between said feed rollers.

3. The combination with a rotary printing couple including a drum; of a cam carried by said drum; an electric switch arranged to be closed and opened by said cam; means arranged to render said couple inoperative when released; an electrically operative releasing mechanism; mechanism arranged to feed sheets of paper between said couple, including a pair of feed rollers one 60 of which is moved toward or from the other

by said cam, and an electric circuit including said switch, said releasing mechanism and a source of current; whereby, said releasing mechanism is operated and the printing couple rendered inoperative when 70 said switch is closed, such closure being consequent upon the omission of a sheet of paper when it should be present between said feed rollers.

4. The combination with a printing couple including a rotary drum; of a cam carried by said drum; means whereby said cam may be rotatably adjusted in definite relation to the printing form on said drum and secured in rigid relation with said shaft; 75 means arranged to render said couple inoperative when released; an electrically operative releasing mechanism; paper feed mechanism controlled by said cam; an electric switch in operative relation with said paper feed mechanism; and, an electric circuit including said switch, said releasing mechanism and a source of current; whereby, said releasing mechanism is operated and the printing couple rendered inoperative when said switch is closed, such closure being consequent upon the omission of a sheet of paper when it should be present.

5. The combination with a rotary printing couple including a drum; of means arranged to render said couple inoperative when released; an electrically operative releasing mechanism; a cam carried by said drum; paper feeding mechanism including a supporting table, stop fingers above said table, a feed roller above said table, a feed roller below said table, means arranged to shift said lower roller to and from co-operative relation with said upper roller including a rock shaft carrying said stop fingers and said lower roller and having means to engage said cam, whereby said stop fingers and feed rollers are rendered alternately operative and inoperative in accordance with the rotary position of said cam; an electric switch arranged to be operated by said cam; another electric switch arranged to be closed when said feed rollers are in contact; and an electric circuit including said switches, said releasing mechanism and a source of current; whereby said releasing mechanism is operated and the printing couple rendered inoperative when both of said switches are closed, such closure being consequent upon the omission of a sheet of paper 105 when it should be present between said feed rollers.

6. The combination with a frame; of a rotary printing couple including a drum; of means arranged to render said couple inoperative when released; an electrically operative releasing mechanism; a cam carried by said drum; paper feeding mechanism including a supporting table, a feed roller above said table, a feed roller below 110

said table, means arranged to shift said lower roller to and from coöperative relation with said upper roller including a rock shaft carrying said lower roller and having 5 means to engage said cam, whereby said feed rollers are rendered alternately operative and inoperative in accordance with the rotary position of said cam; an electric switch arranged to be operated by said cam; another electric switch arranged to be closed 10 when said feed rollers are in contact; and an electric circuit including said switches, said releasing mechanism and a source of current; whereby said releasing mechanism is operated and the printing couple rendered inoperative when both of said switches are closed, such closure being consequent upon the omission of a sheet of paper when it should be present between said feed 15 rollers.

7. The combination with a rotary printing couple including a drum; of a cam carried by said drum; an electric switch arranged to be operated by said cam; means 20 arranged to render said couple inoperative when released; an electrically operative releasing mechanism; mechanism arranged to feed sheets of paper between said couple, including a pair of feed rollers, one of 25 which is moved with reference to the other by said cam; a second electric switch controlled by such movement of a feed roller; an electric circuit including said second switch, said releasing mechanism and a 30 source of current; an electric motor; a rheostat; an electric circuit including said motor, rheostat, and a source of current; and, a 35 third switch arranged to contemporaneously open and close both of said circuits; whereby, said releasing mechanism is operated and the printing couple rendered inoperative upon contemporaneous closure of said switches.

8. The combination with a printing couple; of an electric motor arranged to operate said couple; an electric circuit including said motor and a source of current; means arranged to render said couple inoperative when released; an electrically operative releasing mechanism; movable mechanism arranged to feed sheets of paper between said couple; an electric switch one member of 45 which is moved by movement of said feeding mechanism; an electric circuit including said switch, said releasing mechanism and a source of current; and, a switch arranged to contemporaneously open and close both of said circuits; whereby, said releasing mechanism is operated and the printing couple 50 rendered inoperative when said switches are contemporaneously closed.

9. The combination with a frame; of a rotary printing couple including a drum; means arranged to render said couple inoperative when released; an electrically oper-

ative releasing mechanism; a cam carried by said drum; paper feeding mechanism including a supporting table, a feed roller above said table, a feed roller below said table, and means arranged to engage said cam; whereby said feed rollers are rendered alternately operative and inoperative in accordance with the rotary position of said cam; an electric switch arranged to be operated by said cam; another electric switch arranged to be closed when said feed rollers are in contact; and an electric circuit including said switches, said releasing mechanism and a source of current; whereby said releasing mechanism is operated and the printing couple rendered inoperative when both of said switches are closed, such closure being consequent upon the omission of a sheet of paper when it should be present between said feed rollers.

10. The combination, with a printing couple, of a paper feeding mechanism having two feed rollers, one of which is movable bodily toward and from the other, mechanism operated by the couple for so moving the movable roller, a pair of electric contacts controlled as to their relation by such movement, an electro-magnetic latch electrically connected with said contacts, and means whereby said latch may throw the couple to idle position.

11. The combination of a printing couple, a paper feed therefor including a pair of feed rollers, one of which is bodily movable toward and from the other, mechanism operated by the couple for so moving the bodily movable roller, an arm actuated by such movement and multiplying the range thereof, electric contacts controlled by such arm, and a magnetic latch controlled by such contacts.

12. The combination, with a printing couple, of a paper feed mechanism therefor including a rock shaft, a feed roller carried thereby and bodily movable by the rocking of said shaft, means controlled by the movement of the couple for rocking the shaft, an arm projecting from the rock shaft a distance greater than the distance to the center of the roller whereby the movement of the roller is multiplied at the end of the arm, an electric contact adapted to coöperate with said arm near its free end, and an electro-magnetic latch controlled by such contact.

13. The combination of a rotary printing couple, a paper feeding mechanism comprising a feed roller, a roller adapted to coöperate therewith, a rock shaft having rigid arms carrying said last mentioned roller, a cam on one member of the couple adapted to rock said shaft, an arm secured to said rock shaft and projecting a considerable distance therefrom, an adjustable contact point adapted to coöperate with said arm near its free end, whereby the contact is opened or closed according

to the position of the movable feed roller, an electro-magnetic controlling mechanism connected with such contact.

14. The combination of a rotary printing couple, an eccentric support for the platen, a spring tending to turn such support to move the platen to idle position, a detent restraining such movement, an electro-magnetic latch adapted to withdraw the detent, a paper feed mechanism for the couple, and electric contacts and a circuit for the latch controlled by the feed mechanism.

15. The combination of a printing couple, means for moving the platen to idle position, an electro-magnetic latch for operating said means, said latch comprising a hinged member adapted to act on said means, a spring normally acting on the hinged member, a latch lever engaging the hinged member to hold it inactive, an armature which the latch lever engages, and a magnet controlling said armature.

16. The combination of a printing couple, mechanism for rendering the same idle, an electro-magnetic latch for throwing said mechanism, said latch comprising a hinged member, a spring tending to move it into active position, a latch member for holding it in idle position, an armature for holding the latch member, and a magnet for operating the armature, said hinged member having a projecting finger piece adapted to return it to normal position, and means whereby such movement returns the latch member.

17. The combination, with a printing couple, of an electro-magnetic latch for controlling the same, said latch comprising a magnet, an armature therefor, a latch-lever adapted to engage the armature and be held thereby, a hinged operating-lever adapted to be held idly by the latch lever, a spring tending to move said operating lever into active position, means for returning the operating lever, and means whereby such return 45 returns the latch lever.

18. The combination of a rotary printing couple comprising a printing drum, a platen and upright frame members between which the two are mounted, an eccentric shaft supporting the platen, means tending to turn said shaft to bring the platen to idle position, a detent restraining such movement, a

bar on the inner side of the frame for moving said detent, a push button projecting through the frame and enabling the bar to be moved by hand, an electro-magnetic latch mounted on the inner side of the frame and having an operating member adapted to engage said bar, and a finger piece for returning said latch to normal position, said finger piece projecting outwardly through an opening in the frame, whereby it may be operated from the outside.

19. The combination, with a printing couple, of an electro-magnetic controlling latch therefor consisting of a pivotally mounted operating member, a spring tending to move the same to active position, a pin projecting from the end of said member, a latch lever hinged independently of the member and having a recess which said pin may occupy or clear, an armature adapted to engage and support the latch lever with the pin in the recess, a magnet for said armature, and a finger piece projecting from the operating member and adapted to return it and thereby return the latch lever by reason of the pin coming against the shoulder thereon, provided by the forward wall of the recess, there being a spring to cause the armature to move into engagement with the latch lever when it is moved by the operating member.

20. The combination, with a rotary printing couple, of means adapted to throw the platen of the couple to idle position, a restraining device for said means, an electro-magnetic latch for throwing the restraining device, said latch having a hinged member, a spring tending to move the same to throw the restraining device, a finger piece on the hinged member adapted to return it when thrown, an electro-magnet, and connections between the same and the hinged member, whereby the magnet may release the hinged member to the action of its spring.

In testimony whereof, I have hereunto signed my name at Burlington, New Jersey, this twenty-sixth day of September, 1910.

SAMUEL A. NEIDICH.
